(57) **CLAIM**

The ornamental design for a case for electronic device, as shown and described.

DESCRIPTION

FIG. 1 is a bottom front perspective view of a case for electronic device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a top rear perspective view thereof;

FIG. 9 is a bottom front exploded perspective view thereof, shown with a grip for electronic device in broken lines to show example environment;

FIG. 10 is a bottom front perspective view thereof;

FIG. 11 is an enlarged view of the delineated portion 11 in FIG. 1;

FIG. 12 is an enlarged view of the delineated portion 12 in FIG. 4;

FIG. 13 is an enlarged view of the delineated portion 13 in FIG. 6; and,

FIG. 14 is an enlarged view of the delineated portion 14 in FIG. 7.

The dashed broken lines showing a grip for electronic device case in FIGS. 9 and 10 illustrate environment and form no part of the claimed design. The remaining dashed broken lines in the figures depict portions of the case for electronic device that form no part of the claimed design.

The dot-dash broken lines in the figures delineating portions of the claimed design that are illustrated in enlargements form no part of the claimed design.

(Continued)

The bracket shown in FIG. 9 indicates an association of components; the bracket forms no part of the claimed design.
